SPOON OR SIMILAR ARTICLE

Mathias G. Eckhoff, Porsgrund, Norway, assignor to
Georg Jensens Solvsmedie A/S, Copenhagen, Denmark,
a corporation of Denmark

Application February 28, 1955, Serial No. 34,738

Term of patent 14 years

(Cl. D54—12)

Fig. 1 is a front elevation of a spoon incorporating the said design;

Fig. 2 is a side elevation; and

Figs. 3 to 8 inclusive are enlarged cross-sectional views on the correspondingly numbered section lines of Fig. 2.

The essential features of the design reside in the portions shown in full lines and consist in the handle portion which is concave on its upper face throughout its entire length, said concave face having a continuous bead-like border around its periphery. The lower face of the handle is convex and the sides are continuously curved throughout their length, extending from a narrow, relatively short neck portion through a wider, asymmetrical

intermediate portion and terminating in a slightly rounded tip, the handle tapering in thickness from a very thin cross section at the free end to a thick cross section at the neck, all as shown.

I claim:

The ornamental design for a spoon or similar article, substantially as shown and described.
